(57) **CLAIM**

The ornamental design for a containment member for vacuum apparatus, as shown and described.

DESCRIPTION

FIG. 1 is a front isometric view of a containment member for vacuum apparatus showing our new design.

FIG. 2 is a front elevational view thereof.

FIG. 3 is a rear elevational view thereof.

FIG. 4 is a left side elevational view thereof.

FIG. 5 is a right side elevational view thereof.

FIG. 6 is a bottom plan view thereof; and,

FIG. 7 is a top plan view thereof.

Portions of the drawings in all views that appear in broken lines illustrate an environment of the invention that forms no part of the claimed design.
